J. B. KELLEY, OF BRANDON, VERMONT.

Letters Patent No. 88,791, dated April 13, 1869.

IMPROVEMENT IN COMBINED KNOB-LATCH AND LOCK

The Schedule referred to in these Letters Patent and making part of the same.

To whom it may concern:

Be it known that I, J. B. KELLEY, of Brandon, in the county of Rutland, in the State of Vermont, have invented certain new and useful Improvements in Locks; and I do hereby declare that the following is a full, clear, and exact description of the construction and operation of the same, reference being had to the accompanying drawings, and to the letters of reference marked thereon.

Similar letters of reference relate to the corresponding parts in the several figures.

The object of my invention consists in providing a combination lock and latch, which dispenses entirely with all kinds of springs, can be cast in separate pieces, of iron or other cheap material, is extremely difficult to pick, and may be manufactured very cheaply.

In order that others skilled in the art may be enabled to make and use my invention, I will proceed to describe its construction and operation.

I construct the box C, Figures 1 and 2, which is to contain the various parts, in the usual form, inserting therein, permanently, the pins *a b c*.

The gravitating latch-bolt A, which serves as the lock-bolt and latch, is cast in the form shown in Figure 3, having the shoulder *d*, lug *m*; and stop *r*, cast thereon.

This latch-bolt A is suspended on the pin *a*, upon which it moves freely.

The lever L, which is to operate the latch-bolt A, is cast in the form shown in Figure 4, where the door-knob is represented as being attached. In figs. 1 and 2, the same is shown with the square hole through the large end, for the reception of the rod connecting the inside and outside knobs.

This lever L rotates upon the pinion *n*, which is inserted in the box C.

The tumblers *t t' t''* are cast separately, having the vertical slot *h* and semicircular slot *s*. These are more plainly shown in Figure 5, where they are placed together, and show their relative positions when suspended on the pin *b*, each one, however, moving independently of the other.

These tumblers may be made of any length required,

but must correspond to the length of the guards on the key, Figure 6.

The number of these tumblers may be increased or diminished, as desired, but must always correspond to the number of guards on the key.

To operate this lock as a latch, the tumblers are thrown back into the position shown in fig. 2, and, by its own weight, the latch A will take the position shown in fig. 1, and is prevented from going too far by the shoulder *k* and the stop *r*. To unlatch it, turn the knob to the left, and the small end of the lever L will press upon the lug *m*, and throw the latch A into the position shown in fig. 2; or, turn the knob to the right, and the lever L throws the latch back, by means of the stop *r*. The tumblers *t t' t''* are held in position, fig. 1, and the latch may be used freely, until it is desired to lock it. The key will then turn the tumblers to their position in fig. 1, and the latch-bolt A, which then becomes a lock-bolt, will be held fast by the tumblers, which cannot be forced back until the proper key shall raise each one, so that the pin *c* shall move through the slot *s*, to the position shown in fig. 2.

When locked, the pin *c* being behind the shoulder *w* of the tumblers, the bolt A cannot be forced back till the guards on the key raise all the tumblers sufficiently to pass over the pin *c*. The lock is thus hard to pick, because all the guards must be of the proper length to raise all the tumblers.

It will be observed that this combined lock and latch is only applicable to doors, &c., that maintain a vertical position.

Having thus described my improvement, What I claim, and desire to secure by Letters Patent, is—

The combination and arrangement of the latch-bolt A, lever L, tumblers *t t' t''*, pins *a b c*, and box C, substantially as and for the purposes set forth.

J. B. KELLEY.
